 rial No. 3,374. In the Netherlands January 20,
 1947

8 Claims. (Cl. 252—133)

1

This invention relates to a detergent composition and process for using the same. More particularly, it deals with a composition containing a fatty acid soap which may be used for producing suds in hard water, including sea water.

Previously, compounds such as sodium carbonate and alkali metal phosphates, silicates, pyrophosphates, and the like, have been used to soften hard waters before washing therein with fatty acid soaps. The effect of these water softeners is generally too small to render soap usable in hard water unless uneconomically large quantities of the softeners are added to the water, and it is not always certain that these softeners produce insoluble calcium salts. It has been found that the addition of these softeners with soap in hard water leads to only a small amount of suds or foam formation suitable for washing, and even the addition of sodium carbonate or sodium metasilicate to the hard water before the soap is added produces very little foaming.

Accordingly it is an object to this invention to produce a new, effective, efficient, economical and quickly acting detergent composition which may be used for washing in hard water or sea water.

Another object is to provide a reliable method for using such a composition.

According to this invention, foaming produced by a fatty acid soap in hard water or sea water is insured by first dissolving in the hard or sea water a substance capable of combining with the cations which cause hardness in the water to form substantially little or non-ionized products, before the fatty acid soap is dissolved in the water and has a chance to react with these cations. Thus the composition of this invention comprises two essential ingredients, first a special type of additive to soften the hard water, and second a detergent comprising at least about 50% of a fatty acid soap to produce the desired amount of suds.

The special additives or substances are ones which combine with the cations of the group consisting of calcium, magnesium, ferrous iron, aluminum and manganese which cause hardness in the water. These additives must be readily water soluble and either be dissolved first or be more soluble than the detergent employed in the composition. This may be insured by physically combining the additive with the detergent, such as coating it on the detergent particles, mixing

2

it therewith as smaller sized particles than the particles of the detergent, or by adding the additive to the hard water first and separately from the detergent. In anyone of these three manners the additive will be the first of the two substances to dissolve in the hard water, or at least it will be the first of the two substances to react with these cations causing hardness to form products which will not react with the detergent, and particularly the fatty acid soaps included therein. Specifically, some such additives are: the water soluble fluorides, oxalates, salicylates, formates, ferrocyanides, orthoarsenates, molybdates, metaborates, aluminates, and the like. In the order of their preference, the alkali metal fluorides, oxalates, and ferrocyanides are preferred and particularly the sodium salts thereof.

The detergent in the composition of this invention comprises at least about 50% by weight of a fatty acid soap and preferably more, but minor amounts of other and chemical washing agents which may contain small quantities of the silicates, phosphates, and/or persalts of sodium may be used.

The composition as a whole should be substantially free from soluble (such as alkali metal) metasilicates and carbonates particularly sodium carbonate, although minor percentages of these compounds may be tolerated in the detergent composition.

The amount of special additive in the detergent composition of this invention, is not based on the equivalent quantity of fatty acid but is preferably based upon the degree of hardness of the water, while the amount of fatty acid soap is proportioned to the amount of suds or foaming which is to be made. For example, for each 100° German hardness (1° is equivalent to .0112 gr. per liter of salts producing hardness in the water) about 0.5% by weight of additive, such as sodium fluoride or its equivalent, is required. Thus, if one wishes to wash in water having a 100° German hardness with a 0.5% soap concentration, a 1% mixture of 50 parts soap and 50 parts sodium fluoride or oxalate should be used; and if one wishes to wash with a 1% soap concentration in the same water, 1.5% of a mixture of 100 parts soap and 50 parts sodium fluoride or oxalate should be used.

As previously stated, it is essential to this invention that the water softening additive must be dissolved, or at least react with the cations

causing hardness of the water, before the soap is dissolved in the hard water and reacts with these cations. The most effective way of doing this is to separately dissolve the additive in the water before the soap is dissolved in the water, and practically speaking of the package or containers for the detergent composition may thus contain two separate compartments, one containing the additive which is to be used first and the other containing the soap detergent. These packages may be so physically arranged that when they are opened the additive will first be poured into the water before the soap detergent. Another way of insuring the additive to be dissolved first in the hard water is to use a granular composition in which the particles of soap are coated with a layer of the additive (which may be carried or deposited on another layer of a harmless salt such as sodium sulfate). A third method is to use a mixture of particles of soap detergent and additive, wherein the size of the additive particles is considerably smaller than the size of the particles of the soap detergent so that the smaller particles will be the first to dissolve when both are added simultaneously to water. In either one of the latter two methods, both the additive and the detergent are added simultaneously to the hard water in which washing is to take place, but because of the physical relationship between the two substances of the composition the additive will always dissolve before the soap.

The following examples illustrate the effectiveness of this invention:

EXAMPLE I

One percent of a detergent composition consisting of: (1) 500 grs. of coarse dry granular soap consisting of 60% palm oil fatty acid, 10% tallow fatty acid, and 30% coconut fatty acid, and (2) 500 grs. of finely powdered sodium fluoride was added to water having approximately 100° German hardness (G. H.) and sufficient suds were produced for effective washing.

EXAMPLE II

Two percent of a detergent composition consisting of: (1) 500 grs. of dry coarse granular coconut fatty acid soap, and (2) 1500 grs. of finely powdered sodium fluoride (or oxalate) was found suitable for washing in sea water.

EXAMPLE III

Comparative tests were made for a detergent composition consisting of 250 grs. of dry coarse granular coconut fatty acid soap and 100 grs. of finely powdered sodium fluoride. First the coarse granular coconut soap was added alone to distilled water, then to water having 20° German hardness without sodium fluoride, and finally 0.35% of the composition was added to 20° hard water. The results are indicated below in Table I as the number of cubic centimeters of foam produced at 35° C. at different times.

Table I

	0.25% of soap in dist. water	0.25% of soap in water of 20° German Hardness	0.35% of composition=0.25% of soap+0.1% of NaF in water of 20° German Hardness
Immediately after shaking	Cm. ³	Cm. ³	Cm. ³
after 1 minute	150	0	120
after 2 minutes	140	0	110
unstable	125	0	95
	25	-----	25

From Table I, no washing action is obtained in the hard water of 20° G. H. if no sodium fluoride is added, but when sodium fluoride is added a washing action about equal to that of the soap alone in distilled water is obtained.

EXAMPLE IV

In order to insure that the sodium fluoride and/or sodium oxalate is dissolved in the water before the soap, a coated granular detergent composition according to this invention was prepared in the following manner: Dry coconut soap powder was covered with a layer of molten anhydrous sodium sulfate about equal in weight to that of the soap, then the resulting coated soap particles were coated with wet sodium fluoride (or oxalate). This was accomplished by suspending the sodium fluoride (or oxalate) in a little water to form a super saturated aqueous solution of sodium fluoride (or oxalate), containing an equivalent amount of sodium fluoride (or oxalate) by weight to that of the soap to be used. The salt coated soap was then mixed in this NaF suspension and allowed to solidify, or this suspension was atomized on the coated soap particles in a rotating drum. The resulting product was then dried and contained a film or additional coating of sodium fluoride (or oxalate) which product was suitable for washing in hard water having 20° German hardness, consisting of 15° calcium and 5° magnesium hardness.

EXAMPLE V

The advantage of sodium fluoride and oxalate over previously employed soluble phosphate and sodium carbonate water softeners is shown by comparative tests, the results of which are given in Table II below: In each test 0.25% coconut fatty acid soap was employed, and the cubic centimeters of foam were recorded after shaking in hard water having a German hardness of 20° (15° Ca and 5° Mg) with different amounts of each of the additives disclosed in the table. In each test the additive was dissolved in the water before the soap was added. For comparison 0.25% of the same coconut soap was shaken in water having 0° German hardness, and 210 cubic centimeters of foam was produced.

Table II

Additive	NaF	Na ₂ C ₂ O ₄	Calgon	Na ₄ P ₂ O ₇	Na ₅ (PO ₃) ₆	Na ₂ CO ₃
	Cm. ³	Cm. ³	Cm. ³	Cm. ³	Cm. ³	Cm. ³
.0%-----	30	30	30	30	30	30
.125%-----	190	120	30	30	30	25
.25%-----	228	165	55	45	40	30
.375%-----	250	185	70	55	50	25
.5%-----	250	200	85	80	70	15

Both detrimental calcium hardness and magnesium hardness are prevented by the addition of soluble fluorides and/or oxalates according to this invention.

While there is described above the principles of this invention in connection with specific compositions, it is to be clearly understood that this description is made only by way of example and not as a limitation to the scope of this invention.

What is claimed is:

1. A detergent composition for producing suds in hard water, comprising particles of a suds-producing fatty acid soap, and a water soluble layer of an alkali metal fluoride covering the particles of soap, the alkali metal fluoride of the layer covering the particles of soap being adapted to dissolve in the water before the water contacts the soap and to react with the cations in the water which cause its hardness and to form substantially non-ionized compounds therewith, thereby preventing the reaction of such cations with the soap.

2. A detergent composition as claimed in claim 1 characterized in that the alkali metal fluoride is sodium fluoride.

3. A detergent composition as claimed in claim 1 characterized in that the particles of fatty acid soap are powdered soap in which the particles of soap are covered with a layer of said fluoride.

4. A detergent composition for producing suds in hard water, comprising particles of a suds-producing fatty acid soap, and a layer of water soluble material covering the particles of soap consisting of an alkali metal compound selected from the group consisting of alkali metal fluorides, oxalates and ferrocyanides, the alkali metal compound of the layer covering the soap particles being adapted to dissolve in the water before the water contacts the soap of the covered particles and to react with the cations in the water which cause its hardness and to form substantially non-ionized compounds therewith, thereby preventing the reaction of such cations with the soap.

5. A detergent composition as claimed in claim 4 characterized in that the particles of fatty acid soap are powdered soap in which the particles of

soap are covered with a layer of said water soluble material.

6. A detergent composition for producing suds in hard water, comprising particles of a suds-producing fatty acid soap, and a water-soluble layer of an alkali metal oxalate covering the particles of soap, the alkali metal oxalate of the layer covering the soap being adapted to dissolve in the water before the water contacts the soap of the particles and to react with the cations in the water which causes its hardness and to form substantially non-ionized compounds therewith, thereby preventing the reaction of such cations with the soap.
- 15 7. A detergent composition as claimed in claim 6 characterized in that the alkali metal oxalate is sodium oxalate.
8. A detergent composition as claimed in claim 6 characterized in that the particles of fatty acid soap are powdered soap in which the particles of soap are covered with a layer of said water soluble material.
